US00D607328S

(12) **United States Design Patent**
Himedea

(10) **Patent No.:** **US D607,328 S**
(45) **Date of Patent:** **** Jan. 5, 2010**

(54) **MOUNT FOR PACKAGING OF BATTERY**
(75) Inventor: **Noriko Himeda**, Kadoma (JP)
(73) Assignee: **Panasonic Corporation**, Kadom-shi (JP)
(**) Term: **14 Years**
(21) Appl. No.: **29/312,019**
(22) Filed: **Sep. 24, 2008**
(30) **Foreign Application Priority Data**
Jun. 18, 2008 (JP) 2008-015514
(51) **LOC (9) Cl.** **09-03**
(52) **U.S. Cl.** **D9/457**
(58) **Field of Classification Search** D9/749, D9/721, 705, 700, 658, 655, 652, 457, 455, D9/431, 424, 415; D7/512, 510; D6/526; 493/104; 229/128, 117.03; 220/834; 206/779, 206/775, 705, 701, 563, 553, 471, 469, 459.5, 206/457, 395, 349; D1/127
See application file for complete search history.

(57) **CLAIM**

The ornamental design for a mount for packaging of battery, as shown and described.

DESCRIPTION

The file of this patent contains at least one figure executed in color. Copies of this patent with color figures will be provided by the Office upon request and payment of the necessary fee. FIG. 1 is a perspective view of the front, top and right side of a mount for packaging of battery showing my new design; FIG. 2 is a front view thereof; FIG. 3 is a rear view thereof; FIG. 4 is a left side view thereof; FIG. 5 is a right side view thereof; FIG. 6 is a top plan view thereof; and, FIG. 7 is a bottom view thereof.

**1 Claim, 3 Drawing Sheets
(2 of 3 Drawing Sheet(s) Filed in Color)**
